(57) **CLAIM**

The ornamental design for a stand for visual display boards, as shown and described.

DESCRIPTION

FIG. 1 is a perspective view, taken from the front, illustrating my new design for a stand for visual display boards; FIG. 2 is a perspective view, taken from the rear, illustrating my new design for a stand for visual display boards; FIG. 3 illustrates the design as shown in FIG. 2, in which display boards are mounted to the stand; and, FIG. 4 is a bottom view illustrating the underside of the stand illustrated by FIGS. 1-3.

The display boards, illustrated in broken line in FIG. 3, do not form part of the claimed design.

The portions of FIG. 4 shown in broken line represent unclaimed subject matter.
